UNITED STATES PATENT OFFICE

153,206

DESIGN FOR A GAME BOARD

Fred W. Carroll, Cleveland Heights, Ohio

Application June 20, 1947, Serial No. 139,831

Term of patent 14 years

(Cl. D34—5)

To all whom it may concern:

Be it known that I, Fred W. Carroll, a citizen of the United States, residing at Cleveland Heights, county of Cuyahoga, and State of Ohio, have invented a new, original, and ornamental Design for Game Board, of which the following is a specification, reference being had to the accompanying drawing, forming a part thereof, in which the single figure is a plan view of a game board showing my new design. The cross-hatching of certain areas in the drawing is intended to indicate contrast in tone or color.

The game board is of conventional thickness.

I claim:

The ornamental design for a game board, substantially as shown and described.

FRED W. CARROLL.
